UNITED STATES PATENT OFFICE.

MATTHIAS CROWTHER, OF WEST PITTSTON, PENNSYLVANIA.

HYDRAULIC EJECTOR.

SPECIFICATION forming part of Letters Patent No. 664,037, dated December 18, 1900:

Application filed April 30, 1898. Serial No. 679,377. (No model.)

To all whom it may concern:

Be it known that I, MATTHIAS CROWTHER, a citizen of the United States, residing at West Pittston, in the county of Luzerne and State 5 of Pennsylvania, have invented certain new and useful Improvements in Hydraulic Ejectors; and I do declare the following to be a full, clear, and exact description of the invention, such as will enable others skilled in the 10 art to which it appertains to make and use the same, reference being had to the accompanying drawings, and to the figures of reference marked thereon, which form a part of this specification.

15 My invention relates to hydraulic ejectors or jet-pumps.

My object is to provide a cheap, simple, and effective means of conveying water for considerable distances and over undulating surfaces, particularly in mines.

By the use of my invention I bring the water from the most remote portions of the mine and from dips and chambers to the main sump at the foot of the shaft, where it can be pumped 25 to the surface by means of the ordinary force-pump, and providing at the same time a line of pipe to all parts of the mine. This line of pipe may be used at any time for a fire-line by simply disconnecting or shutting off the 30 ejector.

It is not the purpose of my invention to raise the water to any great height, although it may be raised to the height of twenty feet over an obstruction or up an incline without 35 in any way interfering with the working of the device, and should it be necessary to bring the water to a higher level it may be done by the introduction of another ejector or as many more as the case may require.

40 My device is illustrated in the accompanying drawings, in which like figures of reference refer to like parts in the different views.

Figure 1 is a vertical section of the ejector. Fig. 2 is a horizontal plan of the system in 45 general. Fig. 3 is an elevation of the stand-pipe of the mine, showing the force-pump and sump.

1 is the outlet or delivery pipe; 2, the inlet or suction pipe.

50 3 is the jet. (Shown in the drawings as a part of the nozzle, but which may be made separate and attached thereto.)

4 is the nozzle or supply - pipe, which is threaded, so as to be adjustable, and which I make of some non-corrosive material. 55

5 is an end piece threaded to correspond with and engage the nozzle 4.

6 is a lock or jam-nut to hold the nozzle 4 in place after it has been adjusted in the end piece 5. 60

7 is the packing in the joints.

8 is the choke in the delivery end. (Shown in the drawings as a part of the shell, but which can be made separately and attached to the inside of the shell.) 65

9 is the vacuum-dome; 10, the stand or discharge pipe from the force - pump; 11, the check-valve to prevent the back pressure on the pump 12.

13 is the sump, where the water is emptied 70 by the ejector and taken up by the force-pump.

14 is the foundation for the stand-pipe; 15, the bed of the force-pump.

16 is a shut-off to be used when it is desired 75 to use the pipe-line for fire purposes.

17 represents shut-offs in the pipe-line for the purpose of directing the flow of water to desired points in the mine.

The working of the device is as follows: The nozzle 4 is connected to a water-supply 80 pipe, the source of supply not being essential. For the saving of expense and for convenience, however, I obtain this supply from the stand-pipe at the shaft, where the water is being forced to the surface by the force- 85 pump 12, located at the foot of the shaft, thus providing a pressure equal to the weight of a column of water of a height equal to the distance from the foot of the shaft to the surface of the ground. The water passes through 90 the nozzle 4 and is discharged from the jet 3 with sufficient force to form a vacuum when passing through between the faces of the choke 8, the vacuum-dome 9 rendering the suction formed more perfect in its operation. 95

After the water is started through the nozzle and the suction is thereby started the working of the device is not interfered with by the admission of air, mud, or any solid substance which is not too large to pass through the 100 choke 8.

The working of the device is continuous, requiring no attention whatever, thus saving the expense of pumps in the remote portions

of the mine and the carrying of steam to the pumps; also, dispensing with the services of an attendant, who would be required if pumps and steam were used. The expense of laying 5 a fire-line is also saved by the use of this device.

My device may be used equally as well for a condenser as for an ejector, in which case the exhaust-pipe of an engine or pump is connected to the suction-pipe 2, and the jet of water passing through the steam condenses the same, and the suction thus formed tends to relieve the pressure of the exhaust on the engine or pump.

15 It will be observed that it is essential that the delivery-pipe 1 shall not only be in communication with the jet-pipe leading from the stand-pipe, but also with the suction-pipe 2, so that there will be an uninterrupted flow of 20 water both from the jet-pipe and the suction-pipe into the delivery-pipe and also that when the valve 16 in the delivery-pipe is closed the current or flow from the stand-pipe is reversed and directed into the suction-pipe and out 25 through the branch or branches thereof to the drift where the fire exists.

Having thus fully described my invention,

what I claim as new, and wish to secure by Letters Patent, is—

In an apparatus of the sort described, the 30 combination of a stand-pipe, a reservoir, a force-pump emptying said reservoir into said stand-pipe, an ejector having its discharge-pipe leading to the reservoir and provided with a shut-off valve, the nozzle of said ejector receiving its actuating-jet from the stand-pipe, and a supply-pipe connected to said ejector and leading to the various pools or reservoirs throughout the mine, this supply-pipe and its branches being provided with 40 shut-off valves whereby a portion of the water pumped into the stand-pipe will be employed to automatically collect the water from the various pools of the mine and empty it into the reservoir and the supply-pipe and its 45 branches may, in case of fire, be supplied with water from the stand-pipe.

In testimony whereof I affix my signature in presence of two witnesses.

MATTHIAS CROWTHER.
